Primary Examiner — Katherine Glennon(74) *Attorney, Agent, or Firm* — Zagorin Cave LLP;
 Robert W. Holland(57) **CLAIM**

The ornamental design for an information handling system, as shown and described.

DESCRIPTION

FIG. 1 is a front perspective view of an information handling system comprising the present invention;
 FIG. 2 is a front elevation view thereof;
 FIG. 3 is a rear elevation view thereof;
 FIG. 4 is a right side view thereof;
 FIG. 5 is a left side view thereof;
 FIG. 6 is a top view thereof;
 FIG. 7 is a bottom view thereof;
 FIG. 8 is a bottom perspective view thereof; and,
 FIG. 9 is an open perspective view thereof.
 Broken lines shown in the drawings illustrate portions of the information handling system that form no part of the claimed design.
